FISHERMAN'S BELT

Walter D. Hengst, 6507 Whitesett Ave.,
North Hollywood, Calif.

Filed Apr. 24, 1961, Ser. No. 64,869

Term of patent 7 years

(Cl. D3—10)

FIG. 1

FIG. 2

FIG. 1 is a front elevational view of a fisherman's belt showing my design; and

FIG. 2 is a side elevational view thereof.

The buckle and belt ends are conventional.

I claim:

The ornamental design for a fisherman's belt, as shown and described.
